UNITED STATES PATENT OFFICE.

MATTHEW HOWARD REED, OF CHICAGO, ILLINOIS.

CONCRETE-MIXER.

981,111.

Specification of Letters Patent. Patented Jan. 10, 1911.

Original application filed September 28, 1908, Serial No. 455,101. Divided and this application filed October 29, 1910. Serial No. 589,809.

To all whom it may concern:

Be it known that I, MATTHEW HOWARD REED, a citizen of the United States, residing at Chicago, in the county of Cook and State of Illinois, have invented certain new and useful Improvements in Concrete-Mixers, of which the following is a specification.

My invention refers to improvements in concrete mixers, for mechanically mixing concrete composed of the usual ingredients, crushed stone, sand, cement and water, and it has for its object to provide a construction wherein the concrete may be thoroughly mixed by the rotation of a cylindrical drum provided with angularly arranged blades, means for receiving the ingredients at the lowermost portion of the front end, means for delivering the ingredients into the interior and for preventing their return backwardly, means for discharging the mixed product from time to time as made, together with other features of construction as shall be more fully hereinafter set forth.

The particular object of the invention is to provide an apparatus into which the ingredients may be charged at the lowermost portion so as to avoid the necessity of wheeling or hoisting thereinto from preliminary hoisting platforms or by other hoisting means, as is usually necessary in devices of this class.

The present application is a division of my former application for improvements in concrete mixers filed September 28th, 1908, Serial No. 455,101.

In the drawings which show preferred forms of the apparatus; Figure 1 is a central longitudinal sectional view in normal position. Fig. 2 is an end view in elevation from the front or receiving end. Fig. 3 is a similar view from the rear or discharging end. Fig. 4 is a vertical sectional view on the broken line IV. IV. of Fig. 3, but showing the discharge gate open. Fig. 4^a is a similar view on the line IV^a. IV^a. of Fig. 3 showing the gate operating mechanism in open position. Fig. 5 is a horizontal sectional detail view on the line V. V. of Fig. 2. Fig. 6 is a detail view detached of a portion of the transverse partition, showing one of the segmental openings therein for discharge of the material. Figs. 7 and 8 are front and vertical sectional views respectively, showing modified constructions embodying combined

charging and protecting or mixing blades. 55 Figs. 9 and 10 are similar views showing a further modified arrangement of the parts and a laterally enlarged annular receiving pocket for the material.

In the drawings 2 is the mixer drum or 60 shell provided at its front end with an annular inwardly extending flange 3 forming its front end and having a central receiving opening concentric with the outer larger diameter of the drum, and constituting a 65 front retaining wall, providing an annular pocket for receiving the ingredients or material to be mixed.

4 is a charging chute or rest of suitable form extending from the edge of said flange 70 3 at its lowermost portion, and adapted to receive the material as discharged thereinto and to convey it into said pocket, from any suitable conveying apparatus as a barrow, supported on platform 5, incorporated with 75 the general structure. As will be observed the platform 5 is substantially on a level with the lower edge of the drum, a particular advantage of the invention being that the drum may thus be mounted only sufficiently above the ground level to provide for 80 the necessary framing, thus greatly facilitating the access to the machine by the operator supplying the ingredients. The other end of the drum is closed by a head 6, preferably extending entirely across the area except where open to provide for outlet of the 85 mixed material, as controlled by the outlet gates, hereinafter described.

Extending transversely across the area of 90 the mixer drum near to and somewhat back from its front end, and forming if desired the rear wall of the receiving pocket referred to, is a partition 7, preferably provided with a central opening 8 for inspection 95 of the interior, although said opening may be dispensed with if desired. Said partition 7, in the construction shown, is provided with a plurality of radial openings 9 of segmental or other suitable form as 100 clearly shown in Fig. 6, through which the ingredients are discharged inwardly by the directing blades, to the mixing interior. 10 are charging blades extending angularly outwardly from said partition, radially of 105 the machine and preferably attached to said partition and to the front flange 3 by rivet- 11 represents

protecting blades similarly secured in partition 7 under the opposite side of the openings 9 and also to the shell of the drum. Said charging blades and protecting blades 5 are so disposed, with relation to the partition 7, that they extend outwardly therefrom in opposite directions angularly toward the front and interior respectively, as clearly shown. The object of this construction is as 10 the drum revolves in the direction of the arrow, and as the material is discharged into the peripheral pocket at the front through the charging chute 4, it will be engaged successively by each of the charging blades 10 15 at their lowermost position, carried around and upwardly, falling by gravity inwardly and downwardly to the interior of the mixer. Protecting blades 11, traveling in the same manner will fend the material being mixed 20 away from opening 10 at the lowermost portion, preventing its escape therethrough to the front and providing a clear receiving space for the successive charge of new material.

25 The main interior peripheral wall of the drum is provided with any suitable mixing or carrying elements as one or more mixing blades 12 and one or more mixing plows 13, so disposed angularly across portions of the 30 interior, extending outwardly from the walls and secured thereto, as to best facilitate thorough admixture of the contents. As shown in the drawings, I have employed but one mixing blade 12 and one mixing plow 13, arranged substantially opposite each 35 other, but it will be understood that the number and arrangement of these elements may be varied to suit different conditions of use, and that their depth, angularity, or 40 other features may be changed or modified as desired.

For the purpose of discharging the mixed contents from time to time, I provide one or more discharge gates 14 adapted to open 45 and close a discharge opening *a* through head 6, two such gates being preferably employed as shown in the drawings. Said gates are hinged upon a supporting cross bar 15 adjacent to the inner end of discharge 50 chute *b*, from which they extend outwardly angularly toward and bear against head 6 in normal closed position, (Fig. 1) so that in the rotation of the machine the material will fall against the inner side of the gate 55 and be thrown backwardly into the interior, thus facilitating the mixing operation. Gates 14 are adapted to be opened or closed from either end of the machine during its rotation, avoiding the necessity of stopping, 60 by means of longitudinal rods 16, 16, extending through rear head 6 and through the front cross bar 17 respectively, and provided with terminal grips 18, 19, one at each end at front and back. Pivotaly mounted 65 at 20, 20, to said rods 16, 16, are links 21, 21,

pivotaly mounted at their outer ends at 22, to the extended stems 23, 23, or other suitable portions of gates 14. Links 21 are preferably connected by spring 24, tending to hold the gates normally closed, or normally open. The gates are opened by pushing in rear grip 19, or pulling front grip 19, drawing the gates backwardly on their hinges and the front edges of mixing blade 12 and plow 13 respectively are preferably 75 so located that a portion will receive and support the edge or a part of the gate when opened and the material will be directed toward the discharge gate and opening by the mixing blades, as clearly shown in Fig. 80 4. The hinge 15 of each gate 14 is located adjacent to the inner end of the inclined gate blade or chute *b* forming part of the head 6 surrounding the discharge opening, so that when opened the gate 14 will deliver 85 material from blade 12 to the said gate blade or chute, by which it is discharged from the machine. When thus opened, it will be seen that the contents of the mixing chamber of the drum or a portion of it, may be discharged outwardly to the ground or any 90 suitable receiving receptacle, after which the gates may be readily closed and the operation continued.

The drum is rotated by any suitable 95 means, as a driving pinion or pinions 25, engaging a peripheral rack or racks 26 surrounding the drum. Said racks may be separate or may form a portion of the surrounding supporting band 27 carried on 100 rollers 28 of the supporting framework, as will be readily understood.

In Figs. 7 and 8 I have shown a modified construction in which the separate charging blades and protecting blades are embodied 105 in series of single blades 10' angularly disposed around the front inner portion of drum 2' in a closely consecutive adjacent series. As shown the terminal corner of each of said blades 10' extends beyond the 110 body portion of the next adjacent blade, which is angularly cut out as indicated at 29 for clearance of the entering material. The blades in such construction are somewhat wider than the singly acting blades, 115 extending inwardly toward the center and for the purpose of bracing the inner edges of the blades and providing a bearing for the gate operating rods, one or more longitudinal cross bars 17' are attached to the 120 inner edges of the blades, as shown. By this construction, the material will be received within the front end of the shell back of the flange 3' and will be automatically carried around and delivered into the interior from which it can pass outwardly, due to the construction and arrangement of the 125 series of blades.

In Figs. 9 and 10, the drum 2 is provided with a diametrically enlarged annular re- 130

ceiving pocket 30 formed by radially extended head 31, a surrounding pocket drum 32 and a front retaining flange 33, as clearly shown in Fig. 10. The charging blades 10' and the protecting blades 11' are of substantially the same construction as has already been described as to the principal figures of the drawings, except that blades 10' extend outwardly beyond the main drum 10 diameter to the annular walls of the extended drum 32, thereby crossing the area of the pocket 30 radially at intervals. The advantage of this construction is that the ingredients may be received at a still further point from the center of the drum, lower than in the construction employing a uniformly straight drum, thereby rendering it possible to charge the machine even below the level of any ordinary platform, its operation being substantially the same as that already described.

The operation of the invention will be understood from the foregoing description. The discharge doors are normally closed, the material is charged into the machine as has been described, at the lowermost portion of its receiving pocket, passing inwardly and undergoing the mixing process, being discharged from time to time as needed or when thoroughly mixed. The operation of the machine is rendered comparatively easy by the avoidance of any necessity for carrying the material up to a raised receiving chute, the machine itself operating to automatically receive the material at practically the ground level, and into its interior.

The advantages of the invention will be readily appreciated by all those familiar with this class of apparatus.

40 The invention is comparatively simple in construction, cheap and not liable to get out of order, and will operate continuously without attention.

Having described the invention, what I claim is:—

1. In a mixer, in combination, a revoluble drum, means therein to agitate and mix the material, a continuous series of circularly arranged charging pockets located at one 50 end of the drum within its cylindrical wall and closed at their outer ends, the open inlets of the pockets being turned toward the axis of the drum, a circular head having its periphery contacting with the tops of the 55 pocket walls and set in from the adjacent end of the drum, and means to introduce material to the inlets of the pockets outside of said head.

2. In a mixer, in combination, a revoluble 60 drum, means therein to agitate and mix the material, a continuous series of circularly arranged charging pockets located at one end of the drum within its cylindrical wall and closed at their outer ends, the open inlets of the pockets being turned toward the

axis of the drum, a centrally apertured circular head having its periphery contacting with the tops of the pocket walls and set in from the adjacent end of the drum, and means to introduce material to the inlets of 70 the pockets outside of said head.

3. A concrete mixer consisting of a rotatable drum having means therein to agitate and mix the material and a front annular receiving pocket, a transverse apertured partition set in from the front end of the drum, and an annular series of charging pockets 75 opening from the front annular receiving pocket through the partition to the interior of the drum.

4. A concrete mixer consisting of a rotatable drum having means therein to agitate and mix the material and a front annular receiving pocket, a transverse partition set in from the front end of the drum having 85 radial openings therethrough adjacent to the drum shell, and an annular series of charging pockets formed by inclined blades incorporated with the front annular receiving pocket and adapted to discharge material 90 through the annular openings of the partition to the interior of the drum.

5. A concrete mixer consisting of a rotatable drum having means therein to agitate and mix the material and a front annular receiving pocket, a transverse partition set in from the front end of the drum having radial openings therethrough adjacent to the drum shell, and a central opening, and an annular series of charging pockets 95 formed by inclined blades incorporated with the front annular receiving pocket and adapted to discharge material through the annular openings of the partition to the interior of the drum.

6. A concrete mixer consisting of a rotatable drum having means therein to agitate and mix the material and an enlarged front annular receiving pocket extending laterally beyond the periphery of the drum, a 110 transverse apertured partition set in from the front end of the drum, and an annular series of charging pockets opening from the front annular receiving pocket through the partition to the interior of the drum.

7. A concrete mixer consisting of a rotatable drum having means therein to agitate and mix the material and a front annular inwardly extending retaining flange, a continuous series of circularly arranged charging pockets extending backwardly from said retaining flange having inlets opening toward the axis of the drum and adapted to deliver material to the interior of the drum, and means to introduce material to the inlets 115 of the pockets from outside the drum.

8. In a mixer, in combination, a revoluble drum, means therein to agitate and mix material, a continuous series of circularly arranged charging pockets located at one 125

- end of the drum within its cylindrical wall having open inlets toward the axis of the drum, a circular head having its periphery contacting with the tops of the pocket walls 5 and set in from the front end of the drum, means to introduce material to the inlets of the pockets, and means for discharging the mixed material operable from either end of the drum.
10. 9. In a mixer, in combination, a horizontal revoluble drum having a closed head at its discharge end, an opening and closing gate therein for retaining or discharging the mixed material, a circular head set in 15 from the front end of the drum and dividing the interior middle portion thereof from the front portion, means wholly within the cylindrical wall of the drum and between said wall and the said head to receive the 20 material beyond said head and introduce it to the interior of the drum, and means in the interior of the drum to mix and lift the material and carry it toward the discharge end.
15. 10. In a mixer of the class described, a revoluble drum having a centrally open head at its front outer end, a circular head set in from the said head and across the interior portion of the drum, material inlet devices 30 peripherally arranged around said circular head and exterior thereto but within the cylindrical wall of the drum and said front head and adapted to discharge material into the interior portion of the drum, and means 35 to charge material into said inlet devices from outside the drum.
20. 11. The combination with the revoluble drum having an annular flange or head forming its front end, and an apertured disk set in from said front end, of a series of 40 overlapping diagonally arranged blades secured to said disk extending inwardly and backwardly from said front end with intervening spaces and operable to feed raw material into the interior of the drum upon its rotation.
25. 12. A rotary concrete mixing receptacle having an interior mixing compartment, a front inwardly extending annular flange or 45 centrally open head, and a continuous series of overlapping diagonally arranged blades forming charging pockets extending backwardly from said annular head, said series of pocket blades together forming an annular centrally open wall spaced backwardly 55 from the front centrally open head to the mixing compartment.
30. 13. A rotary concrete mixing receptacle having a front inwardly extending annular flange or centrally open head and a continuous series of overlapping diagonally arranged blades or walls extending backwardly from said annular head having inner terminal ends over which the material 60 is delivered to the interior mixing portion of the drum, said walls being widened or extended inwardly toward the axis of the drum at their inner portions.
35. 14. A rotary concrete mixing receptacle having a front inwardly extending annular flange or centrally open head and a continuous series of overlapping diagonally arranged blades or walls extending backwardly from said annular head having inner terminal ends over which the material 70 is delivered to the interior mixing portion of the drum, said walls having their portions adjacent to the annular head of slightly less width than the distance from the edge of the central opening in the head 75 to the periphery thereof.
40. 15. A rotary concrete mixing receptacle having a front inwardly extending annular flange or centrally open head and a continuous series of overlapping diagonally arranged blades or walls extending backwardly from said annular head having inner terminal ends over which the material 80 is delivered to the interior mixing portion of the drum, said walls having their portions adjacent to the annular head of slightly less width than the distance from the edge of the central opening in the head 85 to the periphery thereof.
45. 16. A rotary concrete mixer drum having a front inwardly extending flange or head, a transverse partition set in from said flange and spaced inwardly from the periphery of said drum to provide passageways for the 90 material, and series of diagonally arranged charging blades secured to said partition, extending in front and backwardly therefrom respectively in the same general direction and providing passageways for the 95 material from the front to the interior of the drum upon its rotation.
50. 17. A rotary concrete mixing receptacle having a front inwardly extending annular flange or centrally open head and a continuous series of overlapping diagonally arranged charging blades spaced apart from each 100 other extending backwardly from said head and constituting an annular wall between the interior of the receptacle and its head, said blades having their portions adjacent to the annular head of slightly less width than the distance from the edge of the central opening in the head to the periphery thereof to provide clearance for the delivery 105 end of a charging chute, and a charging chute extending backwardly over the front 110 annular flange.
55. 18. A rotary concrete mixing receptacle having a front inwardly extending annular flange or centrally open head and a series of overlapping diagonally arranged charging blades extending backwardly from said head having their inner portions widened toward 115 the axis of the drum, and a charging chute 120
60. 19. A rotary concrete mixing receptacle having a front inwardly extending annular flange or centrally open head and a series of overlapping diagonally arranged charging blades extending backwardly from said head having their inner portions widened toward 125 the axis of the drum, and a charging chute 130
65. 20. A rotary concrete mixing receptacle having a front inwardly extending annular flange or centrally open head and a series of overlapping diagonally arranged charging blades extending backwardly from said head having their inner portions widened toward 135 the axis of the drum, and a charging chute 140

extending inwardly over the front annular flange and having its delivery edge lower than the edges of the inner portions of the charging blades.

- 5 19. In a mixer, in combination, a revolvable drum, means therein to agitate and mix the material, a continuous series of circum-
10 larly arranged charging pockets overlap-
ping each other and located at one end only
15 of the drum within its cylindrical wall and closed at their outer ends, the open inlets of the pockets being turned toward the axis of the drum, said pockets being composed of a continuous series of diagonally arranged
20 walls and adapted to receive material from the exterior of the drum endwise and to de-
liver it over the ends of the pockets to the interior mixing portion of the drum upon rotation.
- 20 20. In a mixer, the combination of a revolv-
able drum provided with a centrally ap-
10 pertured head at its receiving end, a series of annularly arranged charging pockets overlap-
ping each other and located at the re-
15 ceiving end only of the drum composed of diagonally arranged walls extending back-
wardly from said head and from the direc-
20 tion of rotation, and having inner widened
25 terminal ends over which the material is de-

livered to the interior mixing portion of the 30 drum, and a charging chute extending in-
wardly through the lower portion of the apertured head having its inner edge lo-
cated farther from the axial center of the drum than are the inner edges of the pocket 35 walls.

21. A mixer consisting of a revolvable drum provided with a centrally apertured head at its receiving end, a series of annularly arranged charging pockets overlap- 40 ping each other and located at the receiving end only of the drum composed of diag-
onally arranged walls extending backwardly from said head and from the direction of rotation, the inner portions of the partition 45 walls extending inwardly toward the axis of the drum beyond the tops of the outer end portions of said walls, and having inner terminal ends over which the material is delivered to the interior mixing portion of 50 the drum.

In testimony whereof I hereunto affix my signature in the presence of two witnesses.

MATTHEW HOWARD REED.
